UNITED STATES PATENT OFFICE

ROBERT DRUMMOND, OF GRANGEMOUTH, SCOTLAND

APPLIANCE FOR DEPOSITING AND/OR PICKING UP PACKAGES

Application filed June 22, 1929. Serial No. 373,038.

The present invention relates to improvements in means for depositing and/or picking up packages from a vehicle in motion, and its principal object is to provide a convenient means for an airplane to deposit a container for mail matter and at the same time to pick up another container while in flight.

Another object of my invention is to provide means of the character described in which the momentum of the mail container to be deposited is transferred to the container to be picked up so that the deposited container loses its momentum and drops while the picked up container receives an initial momentum and allows the entire operation of exchanging one for the other to be performed without any noticeable jar or shock.

A further object of the invention is to provide means of the character described in which the mail container to be deposited is held releasably and is released by impact with the mail container to be picked up, which latter is automatically gripped as the former is released.

It is further proposed in the present invention to provide suitable means for guiding the mail container to be deposited toward the container to be picked up for effecting an impact by which one container is released and the other container is picked up, and by which the momentum is transferred from the former container to the latter.

Further objects and advantages of my invention will appear as the specification proceeds.

The preferred form of my invention is illustrated in the accompanying drawings, in which

Figure 1 shows a front view of my appliance,

Figure 2 a vertical section taken along line 2-2 of Figure 1,

Figure 3 a rear view of my device,

Figure 4 a schematic view illustrating the use of my device, and

Figure 5 a plan view of a guideway leading up to the container to be picked up.

While I have shown only the preferred form of my invention, I wish to have it understood that various changes or modifica-

tions may be made within the scope of the claims hereto attached without departing from the spirit of the invention.

In its preferred form, my device comprises a frame 1 which may be of any suitable form but which is preferably made in the shape shown in the drawings so as to comprise an annular body 2 having a web 3 extending upwardly for connection to a rope or cable 4 by means of which the device may be suspended from an airplane indicated at 6, and having two other webs 7 and 8 extending therefrom radially, the three webs being preferably spaced one hundred and twenty degrees apart. The body portion is provided with a central perforation as at 9 and has a rearwardly-projecting frusto-conical flange 10 adapted to form a seat for the container 11 shown in dotted lines, which latter is filled with mail and is intended to be deposited. The container is held to its seat by means of three arms 12 pivoted in the three webs respectively as at 13 and held in engagement with the container 11 by means of three triggers 14 pivoted in the flange 10 as shown at 15 and formed at one end with hooks 16 extending into slots 17 formed in the arms and adapted to engage with cross pins 18 for holding the arms in operative position relative to the container 11. For nicer adjustment screws 19 are provided in the ends of the arms which are adapted to enter a groove 20 formed in the circumference of the container 11. Strong springs 21 connect the arms with stationary points 22 of the webs and tend to pull the arms away from the container for releasing the latter, the springs being held under tension by the triggers 14.

The three triggers 14 are shaped so that their free ends extend through the central perforation in the body 2 and into contact or close proximity with a diaphragm 23 mounted in front of the opening in the body 2 and supported by means of three spring arms 24. It will be noted that when this diaphragm is struck by a body from in front, it will release the three triggers and allow the springs 21 to withdraw the arms 12 from holding engagement with the container 11, whereby the latter is made to drop.

The diaphragm 23 is preferably formed with a plurality of lips 26 preventing the diaphragm from passing through the central perforation.

5 The arms 12 are formed with extensions 27 in front of the frame, and the arms and extensions are shaped in such a manner that when the arms are in holding engagement with the container 11 the extensions in front 10 are substantially parallel and leave an opening between the same so that they may conveniently straddle a second container 29 of substantially the same proportions that may be supported on a suitable frame indicated at 15 28 in Figure 4 with freedom of removability. The extensions 27 have suitable gripping members 27' mounted in the ends thereof. It will be seen that when the diaphragm 23 is made to strike the second container shown 20 at 29, the triggers 16 release the container 11 and the springs 21 draw the arms 12 away from the container while at the same time causing the extensions 27 to grip the new container 29. At the same time the impact 25 between the two containers serves to transmit the momentum of the first container to the second container so that the first container drops while the second container receives an initial momentum, allowing the frame to continue its flight without any interruption or 30 any shock caused by the exchange of the two containers.

Where my appliance is to be used in connection with airplanes, some special means 35 should be provided for guiding the appliance for proper impact with the stationary container. For this purpose I provide a rudder 30 which causes the entire device to travel through the air without turning and twisting 40. For guiding the device directly up to the stationary container, I preferably provide a track 31 wide open at one end and narrowing down at the other end so that the pilot in approaching the station where the exchange is to be made can guide his airplane in such a manner that the rudder enters at the wide open end of the track and travels inside of the track for bringing the container 11 of his appliance into exact vertical alignment 45 with the container 29 supported above the track. For securing horizontal alignment, different schemes may be resorted to, one of the simplest schemes probably being the arrangement of two rollers 32 disposed on opposite sides of the rudder and adapted to ride 50 on the track, the rollers, of course, being disposed so as to bring the container 11 into the horizontal plane of the stationary container 29.

60 The containers for the mail are preferably constructed of standard dimensions, and it might be well to have the front end of the container separated from the rest by a divisional wall indicated at 33 so as to provide 65 a front chamber which might be filled with

compressed air through any suitable means as, for instance, the valve 34, to provide a cushioning effect. The container itself would preferably be in the form of a cylinder and might have a piston 35 reciprocable therein 70 adapted for operation by means of an operating element 36 for forcing the mail contained within the container into a close compact mass. The container might have a quarter section of its circumference hinged along 75 the top as shown at 37 for giving access to the interior.

The manner of using my appliance will be readily understood from the foregoing description. The mail to be deposited is arranged in the container while the latter is in the airplane, whereupon the container is fastened in my appliance between the arms 12 with its front end resting against the flange 10 and with the triggers set in the manner 80 previously described. The appliance is then lowered from the airplane, and the pilot when approaching the track 31 guides his airplane so that the rudder enters between the two rails of the track and the rollers 32 ride on 85 the track. As the appliance advances in this position, it is centrally aligned with the container 29 which has been filled with mail at the station and which is to be exchanged for the container 11. As the diaphragm is struck 90 by the container 29, it releases the triggers 14, allowing the arms 12 to snap away from the container 11 which drops, while the extensions 27, under the influence of the springs 21, grip the container 29. The impact between the two containers serves to transfer the momentum from container 11 to container 29, causing the first container to drop and the second container to continue with an initial speed equal to the former speed of the container 11, so that the entire transaction takes 100 place without any strain on the rope 4 and without any sudden pulling or jerking on the airplane. In fact, the entire operation is performed so smoothly that the same will not be 105 felt at all by the pilot and passengers in the airplane, and the latter may pursue its course 110 without any interruption.

I claim:

1. In a device of the character described, 115 means for moving an object for impact with an object removably mounted on a supporting element, and means actuated by the impact for releasing the first object and for gripping the second object.

2. In a device of the character described, a frame, means for moving the same for impact with an object removably mounted on a supporting element, means carried by the frame and actuated by the impact for gripping the object, and means actuated by the impact for transmitting initial momentum to the object substantially equal to the momentum of the frame. 125

3. In a device of the character described, a 130

frame, means for suspending the same from an airplane, means associated with the frame for exchange while in flight of an object carried by the frame for an object removably mounted on a supporting element, and means for guiding the frame to the object comprising a rudder associated with the frame and a stationary guideway for the same.

4. In a device of the character described, a movable frame having a plurality of coacting members adapted to releasably hold an object, means carried by the frame for holding the members in active position, and an element supported on the frame adapted to act on the members for releasing the object when the said element strikes a second object.

5. In a device of the character described, a movable frame having a plurality of coacting members adapted to releasably hold an object, a plurality of triggers pivoted in the frame and adapted to hold the members in active position and a diaphragm mounted in the frame in front of the object adapted to release the triggers when the diaphragm is struck by a second object.

6. In a device of the character described, a movable frame having a plurality of coacting members adapted to releasably hold an object, means carried by the frame for holding the members in active position, and an element supported on the frame adapted to act on the members for releasing the object when the said element strikes a second object, the said members having coacting extensions and having spring means active thereon for causing the extensions to grip the second object when the first object is released.

7. In a device of the character described, a movable frame having means for holding an object, means responsive to impact with a second object for releasing the first object and means responsive to the same impact for gripping the second object while the first object is released, whereby the momentum of the first object is transferred to the second object.

8. In a device of the character described, a movable frame having a plurality of coacting arms adapted to releasably hold an object, a diaphragm mounted in the frame in front of the object, triggers mounted on the frame for holding the arms in active position on the object and extending into operative proximity of the diaphragm for operation by the latter when the diaphragm is struck by a second object.

9. In a device of the character described, a movable frame having a plurality of coacting arms adapted to releasably hold an object, a diaphragm mounted in the frame in front of the object, triggers mounted on the frame for holding the arms in active position on the object and extending into operative proximity of the diaphragm for opera-

tion by the latter when the diaphragm is struck by a second object, the arms having extensions projecting forward of the diaphragm so as to encircle the second object when the diaphragm approaches the same and having spring means causing the extensions to grip the second object when the triggers are released.

10. In a device of the character described, a frame having means associated therewith for releasably holding an object, means for removably supporting a second object for impact by the first object whereby momentum is transferred from the latter to the former and means operable in response to the impact for releasing the first object and for gripping the second object.
